Primary Examiner — Jack Reickel*Assistant Examiner* — Keith J Wilson(74) *Attorney, Agent, or Firm* — Fletcher Yoder, P.C.(57) **CLAIM**

The ornamental design for a spray gun, substantially as shown and described.

DESCRIPTION

FIG. 1 is an isometric view of a spray gun;

FIG. 2 is a right side view of the spray gun of FIG. 1;

FIG. 3 is a front view of the spray gun of FIG. 1;

FIG. 4 is a left side view of the spray gun of FIG. 1;

FIG. 5 is a rear view of the spray gun of FIG. 1;

FIG. 6 is a bottom view of the spray gun of FIG. 1; and,

FIG. 7 is a top view of the spray gun of FIG. 1.

The broken lines shown represent portions of the spray gun that form no part of the claimed design.

1 Claim, 7 Drawing Sheets(56)
